STAND

Louis A. Wieland, Pittsburgh, Pa.

Application April 3, 1953, Serial No. 24,335

Term of patent 7 years

(Cl. D33—14)

To all whom it may concern:

Be it known that I, Louis A. Wieland, a citizen of the United States, residing at Pittsburgh, in the county of Allegheny and State of Pennsylvania, have invented a new, original, and ornamental Design for a Stand, of which the following is a specification, reference being had to the accompanying drawing, forming part thereof;

Fig. 1 is a perspective view of a stand showing my new design, the drawer beneath the top being shown in closed position.

Fig. 2 is a perspective view thereof with the drawer in open position.

Fig. 3 is a top plan view thereof on a reduced scale as seen in Fig. 1.

I claim:

The ornamental design for a stand, substantially as shown and described.

LOUIS A. WIELAND.
